UNITED STATES PATENT OFFICE.

WILHELM LORENZ, OF CARLSRUHE, BADEN, GERMANY.

CARTRIDGE-CASE.

SPECIFICATION forming part of Letters Patent No. 293,257, dated February 12, 1884.

Application filed May 21, 1883. (No model.) Patented in Germany March 19, 1882, No. 19,677, and August 24, 1882; in France May 27, 1882, No. 149,236; in Belgium July 1, 1882, No. 58,359; in England July 3, 1882, No. 3,137, and in Austria-Hungary October 12, 1882.

To all whom it may concern:

Be it known that I, WILHELM LORENZ, of the city of Carlsruhe, in the Grand Duchy of Baden, in the Empire of Germany, have invented certain new and useful Improvements 5 in Cartridge-Cases, of which the following is a specification.

I have devised a cartridge-case in two thicknesses, the outermost being separable from the 10 innermost and allowed to remain in the cartridge-chamber of the gun, the inner case being withdrawn after the firing. One such double-case cartridge may serve for a long period, the outer shell or portion thereof remaining in the gun, and allowing the use of a great number of metal-case cartridges to be 15 used, being introduced in succession within the shell or outer portion of the first cartridge as it remains fast in the gun. When it is desired to use ordinary pasteboard cartridges again, the outer shell of the first cartridge may be removed by the fingers or by any suitable instrument.

For sporting fire-arms of all descriptions, in 20 particular for Lancaster and Lefaucheux guns, paper or pasteboard cartridge-cases have heretofore been mostly used, for the reason that while the outer diameter of metal cartridge-cases were made to correspond with the 25 cartridge-chamber of the gun and with the outer diameter of the pasteboard cases, the inner diameter of the metal case was too large, on account of the less thickness of the metal cases. Thus the metal cases contained a greater quantity 30 of powder and shot, and required larger closing-plugs at the front of the cases than the pasteboard cases, and the movement of such large plugs or wads into the smaller bore of the gun had a detrimental effect on the behavior 35 of the gun. It is not expedient to use metal cases of the same thickness as the cardboard cases. These inconveniences are effectually avoided by the present improved metal cartridge-case provided with an outer removable metal jacket. The outer diameter of this 40 jacket corresponds accurately with the outer diameter of the corresponding pasteboard cartridge-case and with the cartridge seat or chamber of the gun, while at the same time

the inner diameter of the metal case also corresponds with the inner diameter of the pasteboard case, thus insuring an equal charge of powder and an equal-sized plug and the ordinary successful action on firing. 50

The accompanying drawings form a part of 55 this specification, and represent what I consider the best means of carrying out the invention.

Figure 1 is a side elevation, showing the improved cartridge with the inner shell and its 60 contents partially drawn out from the outer shell. Fig. 2 is a corresponding front view. Fig. 3 is a longitudinal section, showing the cartridge-case in complete condition for use. Fig. 4 is half of a corresponding front view. 65 Fig. 5 is a complete front view. Fig. 6 is a side view of the outer shell detached. Fig. 7 is an end view of the same. Figs. 8 and 9 show a modification. In the previous views the outer shell as well as the inner is represented as drawn from a continuous tube. These Figs. 8 and 9 show the outer shell 70 formed from a previously-rolled piece of sheet metal, the metal having been carefully rolled to the proper uniform thickness, cut by dies 75 or otherwise, and bent around by hand or by machinery, and forming a complete cylinder, except that it is open for a narrow space extending the whole length. Fig. 8 is a side view, and Fig. 9 an end view. 80

Similar letters of reference indicate corresponding parts in all the figures.

A is the inner shell, formed in all respects like an ordinary metal shell, but with a less external diameter than is required to fill the 85 cartridge-chamber of the gun.

B is the outer jacket, having an external diameter just sufficient to tightly match the cartridge-chamber of the gun, and having an internal diameter adapted to receive the inner shell and to support it. 90

In loading the cartridge, the inner shell is held in any ordinary or suitable manner to receive the proper quantity of powder and shot, the covering plug or wad (not represented) 95 being applied and lightly secured in the ordinary manner. Then the outer shell, B, is applied.

In use, the entire cartridge-case, including both the inner shell, A, and the outer shell, B, are inserted in the cartridge-chamber of the gun, strongly locked in any ordinary or 5 suitable manner, and either immediately or at any period thereafter, when desired, the gun is fired in any ordinary or suitable manner.

I have indicated a percussion-cap adapted to be fired by a smart blow from a firing-pin to be operated by the lock of the gun, as will be understood. The straining due to the violent expansion of the powder is effectually resisted by the thin inner shell, A, by reason of its being supported by the exterior surface of the 15 outer shell or metal jacket, B. This outer shell or casing, B, is also expanded against the walls of the cartridge-chamber, and is thus held in its desired position without the employment of an end flange, which I find interferes with the proper seating of the cartridge and prevents a tight joint. The first 20 cartridge, having the outer shell, B, being properly positioned and exploded, the shell B is retained in the cartridge-chamber.

25 My improved cartridge-case can be used in guns adapted for pasteboard cases. In using these improved metal cases the outer jacket, B, remains in the chamber or cartridge-seat of the gun after firing and withdrawing the 30 case, so that only the first cartridge used requires to have the jacket. If it be subsequently desired to shoot with pasteboard car-

tridges again, all that is necessary to prepare the gun is to simply draw out the outer shell, B, instead of allowing it to remain there 35 longer. This arrangement is applicable for all calibers of Lancaster, Lefaucheux, and analogous sporting-guns.

I am aware of Patent No. 163,154, of 1875, in which the inner shell and head are made 40 separate, and in which the outer shell has a flange which does not enter the cartridge-chamber of the gun, and such construction is not sought to be covered in this application.

Having thus described the nature of my invention and in what manner the same is to be 45 performed, I claim—

The compound cartridge-case described, having an inner shell, A, with its closed rear and flange, as usual, but with a body of less 50 thickness than is required to fill the cartridge-chamber of the gun, in combination with an external removable shell, B, in the form of a plain cylinder, adapted for joint operation relatively to each other and to a breech-loading gun, substantially as herein specified. 55

In testimony whereof I have hereunto set my hand, at Berlin, this 13th day of March, 1883, in the presence of two subscribing witnesses.

WILHELM LORENZ.
